UNITED STATES PATENT OFFICE.

MOSES N. PUGH, OF PAYNE, OHIO.

LIFTING-TOOL.

1,234,565.

Specification of Letters Patent. Patented July 24, 1917.

Application filed March 10, 1917. Serial No. 153,954.

To all whom it may concern:

Be it known that I, MOSES N. PUGH, a citizen of the United States, residing at Payne, in the county of Paulding and State 5 of Ohio, have invented certain new and useful Improvements in Lifting-Tools, of which the following is a specification, reference being had to the accompanying drawings.

10 This invention relates to lifting tools and has for its primary object to provide a very simply constructed and serviceable device for conveniently lifting rails, ties, beams, and other heavy objects whereby the same 15 may be moved from place to place.

It is a more particular object of the invention to provide a device for the above purpose including two lifting levers each provided with a hook on one end and a 20 hand-hold on its other end, and means permanently connecting said levers but permitting of their relative movement whereby the lifting hooks may be suitably spaced from each other.

25 It is also an important object of the invention to provide a lifting device which will be exceedingly durable in its construction and, at the same time, very simple so that the device can be manufactured and sold at 30 relatively small cost.

With the above and other objects in view, my invention consists in the novel features of construction, combination and arrangement of parts to be hereinafter more fully 35 described, claimed and illustrated in the accompanying drawing, in which,

Figure 1 is a perspective view showing my improved lifting device applied to a rail;

40 Fig. 2 is a longitudinal section through the connecting member for the lifting levers; and

Fig. 3 is a section taken on the line 3—3 of Fig. 1.

45 Referring in detail to the drawing, 5 designates two similar lever members, each of said members being in the form of a cylindrical rod of requisite diameter, one end of which is formed into a hand ring or loop 6. A hook 7 is formed upon the other end 50 of the rod and projects therefrom in a plane at right angles to the plane of said hand loop.

These lever members are permanently connected to each other by means of a heavy 55 coiled wire rod 8, the coils of said rod being

closely engaged with each other and of such diameter that the two cylindrical lever members may be readily shifted through the coils with respect to each other. The coiled 60 connecting rod is not, however, of sufficient diameter to admit of the hooks 7 being withdrawn through the coils, whereby the lever members could be separated. This coiled 65 rod 8 provides a bearing for the lever members at their intersecting portions, each of said members engaging with the opposite ends of the coiled rod at diametrically opposite sides thereof, as clearly shown in Fig. 2 of the drawing. 70

From the above description, taken in connection with the accompanying drawing, the construction and manner of use of the device will be readily understood. In Fig. 1, I have shown my invention applied to a 75 rail R, and in the application of the lifting levers, it will be understood that the same are shifted through the coiled rod 8 to properly space their hooks 7 so that they may be engaged beneath the base flange of 80 the rail at opposite edges thereof. The hand loops 6 are then grasped, each by one hand, so that the rail can be readily lifted. With one of my lifting devices thus applied to each end of the rail, it will be seen that the 85 rail can be very easily handled and moved from one place to another. The device may also be applied in a similar manner to posts, beams, plates, or other heavy objects which it is desired to move. It is, of course, to be 90 borne in mind that the central bearing member 8 may be of any desired length and the rods or levers can also be of various thicknesses and diameters in accordance with the particular use to which the device is to be 95 applied. Therefore, while I have herein shown and described the preferred construction and arrangement of the several parts, it will be understood that the device is susceptible of considerable modification there- 100 in and I reserve the privilege of adopting all such legitimate changes as may be fairly embodied within the spirit and scope of the invention as claimed.

Having thus fully described my invention, what I desire to claim and secure by Letters Patent is:—

1. An adjustable lifting device comprising two similar lever members each having a hand-hold on one end, and a lifting hook 110 on its other end, and a cylindrical bearing member through which the lever members

are longitudinally movable with respect to each other and by which they are permanently connected.

2. An adjustable lifting device comprising two similar lever members each having a hand-hold on one end and a lifting hook on its other end, and a closely coiled guide rod through which said lever members are longitudinally movable with respect to each other and by which they are permanently connected together, said rod constituting a bearing for the said lever members.

3. An adjustable lifting device comprising two cylindrical lever rods each having a hand loop formed on one end and a lifting hook on its other end disposed in a plane at right angles to the hand loop, and a closely coiled wire rod through which said lever rods are longitudinally movable with

respect to each other and by which they are 20 permanently connected to each other, each of the lever rods having bearing engagement with the ends of said coiled rod at diametrically opposite points.

4. An adjustable lifting device comprising 25 two lever members each having a lifting hook on one end, and a bearing member through which said lever members extend in relatively opposite directions and in which said lever members are longitudinally adjustable relative to each other to properly space the lifting hooks.

In testimony whereof I hereunto affix my signature in the presence of two witnesses.

MOSES N. PUGH.
